UNITED STATES PATENT OFFICE.

CARL G. OLSON, OF CHICAGO, ILLINOIS, ASSIGNOR TO ILLINOIS TOOL WORKS, OF CHICAGO, ILLINOIS, A CORPORATION OF ILLINOIS.

TOOL HOLDER AND DRIVER.

1,232,714.

Specification of Letters Patent. Patented July 10, 1917.

Application filed March 12, 1917. Serial No. 154,139.

To all whom it may concern:

Be it known that I, CARL G. OLSON, a citizen of the United States, residing at Chicago, in the county of Cook and State of Illinois, have invented a certain new and useful Tool Holder and Driver, of which the following is a specification.

My invention relates to spindles for use in various machines or machine tools such as 10 lathes, milling machines, woodworking machines, and others. My device is especially adapted for high speed work, and in its preferred form, has a cylindrical housing of standard size, thus enabling the device as a 15 whole to be mounted in the machine. The spindle has a taper mouth in which grinding and various cutting tools may be inserted, thus rendering the device "universal" in the sense of being applicable in a great 20 many different situations and for a great many different specific purposes. The device constitutes both a holding and a driving means and may therefore be regarded as a combination tool holder and driver. The object of the invention is to produce a simple 25 and efficient device having the above mentioned characteristics. Among other things, it is my purpose to provide a device having simple and efficient bearings for the rotating 30 part; a spindle and pulley which may be held assembled by the same element which holds the chuck or tool in place; and efficient oiling means which will keep the parts lubricated and require very little attention. 35 Another object is to provide simple and sure acting means for holding the bearing bushings in place and the other elements assembled therewith. These and other contributory objects will become more readily understood from the following description and 40 claims:

The objects are accomplished by the mechanism illustrated in the accompanying drawings, in which:

45 Fig. 1 is an axial section of the assembled device.

Fig. 2 is a transverse section on the line 2—2, Fig. 1, looking in the direction of the arrows.

50 Fig. 3 is a transverse section on the line 3—3, Fig. 1, looking in the direction of the arrows.

Fig. 4 is a side view of the assembled device.

55 Fig. 5 is a perspective view of the split taper bushing.

Similar numerals refer to similar parts throughout the several views.

The housing 1 is cylindrical and is of reduced diameter at each end, at which points 60 it is externally threaded to take the caps 2 and 3 and the lock nuts 4 and 5. The housing is of some standard diameter, so that it may be introduced and held in various standard machines. Near its central portion it has 65 an oil chamber 6 into which a suitable lubricant may be introduced through a screw plug 7. At the back end of the housing there is formed a taper bearing 9 which receives a bushing 10. This bushing is split as shown 70 in Fig. 5 so as to be adjustable for wear. This and the front bushing 11 are made of special bearing material and form journals for the rotating spindle 12. Bushing 10 is held in position by cap 2, previously mentioned. This cap screws over the threaded back end of the housing and has an inwardly turned annular shoulder 14, which forms an end thrust bearing by which bushing 10 may be adjustably forced into its taper seat in the 75 housing. Between cap 2 and lock nut 4 is a thin washer 15 having a tongue 16 which fits into a groove 17 extending longitudinally in the threaded back end of the housing. The arrangement is clearly shown in 80 Fig. 2 as well as Fig. 1.

The front bushing 11 bears at the inner end against an inwardly extending annular flange 19. The front end of the bushing is tapered to form a seat for the taper collar 20 90 formed upon the front end of spindle 12. The front surface of this collar is in a plane transverse to the axis of the spindle and thus forms an abutment or shoulder for a ring 22 which acts as a thrust bearing. By preference, this ring is prevented from turning 95 by two pins 23 which extend into the annular shoulder 24 formed upon the inside of cap 3. The mouth of the spindle projects beyond the shoulder 20 and is conically tapered to 100 receive the shank 25 of a chuck or tool. It is assumed that the chucks or tools intended to be used with my device shall have conically tapered shanks each having an interiorly threaded socket 26 for receiving the 105 threaded end of the holding rod 27. At the back end rod 27 has an annular shoulder 28 which bears against the drive pulley 29. Said pulley has a conical bore which fits over the conically tapered end 30 of the spindle. 110 By reference to Fig. 1 it will be seen that when the holding rod 27 is tightened, it both

draws the shank 25 firmly to a seat in the tapered mouth of the spindle and draws the pulley 29 firmly to a seat on the conical tapered portion 30 at the back end of the spindle. Thus the parts are held assembled through the medium of a single holding element. Cap 3 like cap 2 is locked in position by means of a lock nut 5 assisted by the washer 32 which, like the washer 15, has a tongue 33 fitting in the longitudinal groove 34 in the reduced threaded portion at the front end of the housing.

In practice, the housing with the spindle in it and the fastening devices in place is fastened in the lathe or whatever tool the device is to be employed in. As the housing is of standard size and the caps 2 and 3 and nuts 4 and 5 are cylindrical and of the same diameter as the housing, the device is insertable as a single standard unit. When this has been done the operator selects the chuck or tool that he wants to work with and inserts its conically tapered shank into the correspondingly tapered mouth of the spindle. He then inserts the holding rod 27 and screws it into the socket 26 in said shank. As previously stated, this serves both to hold the shank in position and to hold the pulley 29 firmly secured to the back projecting end of the spindle. The spindle may now be rotated at high speed through the driving pulley 29 and the parts will maintain their position with security. The chamber 6, being filled with lubricant, keeps the bearings well oiled for a long period of time without any particular inspection. When the bushing 10 wears, the wear may be taken up by readjusting the cap 2.

By looking at Fig. 4 of the drawings, it will be seen that the entire device, practically speaking, presents the appearance of a small, unitary cylinder made up of a plurality of component parts, but nevertheless, having the shape and appearance of a single unitary structure.

Having thus described my invention, what I claim as new and desire to secure by Letters Patent, is:

1. A portable, unitary tool holder and driver comprising a cylindrical housing adapted to be fastened in a lathe or similar machine, a spindle journaled in said housing, said spindle having a longitudinal bore and being conically chambered at the front end for receiving the shank of a chuck or tool, and a holding rod passing longitudinally through the spindle and screwing into the end of the shank for holding the same tightly seated in the mouth of the spindle.

2. A standardized portable tool adapted to be fastened in a lathe or similar machine,

the tool comprising a cylindrical housing which is longitudinally chambered, a spindle journaled in said housing, said spindle being longitudinally chambered and having a collar at one end which is conically tapered on one side and plane on the other whereby the spindle is held against longitudinal movement in the housing, the mouth of the spindle being conically tapered to receive the conically tapered end of a chuck or tool, a pulley fastened on said spindle beyond the back end of the housing, and a holding rod bearing against the pulley to hold it upon the spindle, said rod passing through the spindle and screwing into the shank of the chuck or tool for holding it firmly seated in the spindle.

3. In a device of the class described, the combination of a housing, a spindle journaled therein, said spindle being longitudinally chambered and having a flaring mouth at the front end and a conical exterior at the back end, the spindle projecting beyond the back end of the housing, a pulley having a conical bore fitting the conical back end of the spindle, and a holding rod having a shoulder bearing against the pulley for holding it fast upon the spindle, said rod screwing into the end of the shank of a chuck or tool for holding said shank firmly seated in the flaring mouth at the front end of the spindle.

4. In a portable tool holder and driver, a cylindrical housing having at one end a conically tapered bearing, a conically tapered split bushing fitting into said bearing, and a cap screwing over the adjacent end of the housing for forcing said bushing into said taper bearing, a spindle rotatably mounted in said bushing, means for driving said spindle, and means for holding the shank of a chuck or tool fast to said spindle.

5. In a portable tool holder and driver, a cylindrical housing which is longitudinally chambered and has an inwardly projecting flange near one end, a bushing within the housing bearing at its inner end against said flange, said bushing having a tapered mouth, a spindle passing through said bushing and having a tapered shoulder bearing against the tapered mouth of said bushing, the front end of said shoulder being plane and transverse to the axis of the spindle, a thrust bearing screwing onto the end of the housing, and engaging the plane surface of said shoulder for holding the spindle seated upon the bushing, means for driving said spindle, and means for holding the shank of a chuck or tool in said spindle.

In witness whereof, I have hereunto subscribed my name.

CARL G. OLSON.
